UNITED STATES PATENT OFFICE

1,923,188

MEANS FOR INTERMITTENTLY DELIVERING JAM, CUSTARD OR OTHER MATERIAL IN PREDETERMINED QUANTITIES

Einar Christiansen, Birmingham, England

Application March 5, 1932, Serial No. 597,063, and
in Great Britain June 22, 1931

4 Claims. (Cl. 107—29)

This invention comprises certain improvements in or relating to means for delivering jam, custard or other material in predetermined quantities, and particularly relates to a machine such as set forth in my prior patent specification Serial No. 495,529, filed November 13th, 1930.

According to the present improvements, a pie casting or other receptacle for receiving the material from the discharge nozzle is placed on a table which is automatically raised to the discharge nozzle for receiving the material, and after discharge the table is lowered in order to ensure that the material in the receptacle will be separated from the material in the discharge nozzle. Further in order to ensure that a variable quantity of material will not be left on the discharge nozzle means may be provided for separating any material which may be left on or projecting from the discharge nozzle. The tins or the like containing the pie castings are adapted to be automatically fed on to the movable table when in the lowered position, and the means are conveniently such that as one tin is pushed on the table the previous positioned tin is pushed therefrom.

Referring to the drawings:

Figure 1 is a front view of a machine constructed according to this invention.

Figure 2 is an end view of the machine looking in the direction of the arrow a Figure 1.

Figure 3 is a sectional plan view on the line 3—3 of Figure 1 and shows the feed slide mechanism for the tins or the like in the two extreme positions, and

Figure 4 is an underside plan view of the dividing or cut off device hereinafter referred to.

According to a convenient embodiment of this invention, the device for intermittently supplying predetermined quantities of material is conveniently a machine as set forth in my prior specification, Serial No. 495,529, filed November 13th, 1930, in which a horizontally reciprocating piston 1 is adapted to draw the material from a hopper 2 into the piston cylinder 3 and to eject the same therefrom through a downwardly directed nozzle 4. The delivering means is mounted on a stationary table 5 which supports a vertically movable table 6. This table 6 is mounted on the head of a rod 7 which is mounted in a boss or bearing 8 depending from the underside of the stationary table 5. The end of this rod is bifurcated and holes 9 are provided in the bifurcations for receiving a pin 10 which thus passes across the slot. A series of holes are provided so that the position of the pin may be ad-

justed in accordance with the height to which the table 6 is required to be raised. A lever 11, pivoted intermediate its ends, is adapted at one end to pass through the said slot and at the other end to co-operate with a cam or arm 12 mounted on a revolving shaft 13. The tail end 11a of the lever 11 is curved and has conveniently a radius of curvature corresponding with the length of the arm 12 operating such lever. The end of the arm 12 carries a roller 14 which bears on the lever end as the arm 12 rotates the lever 11 is reciprocated. The end of the lever engaging the pin 10 on the table spindle 8 aforementioned is conveniently divided and the outer end 11b is pivotally mounted on the main portion of the lever and moves against an abutment 15 to prevent relative upward movement but allows a downward relative movement. This downward relative movement is normally prevented by a spring 16 which has sufficient tension to keep the outer end 11b of the lever in alignment with the main portion of the lever during the normal action. Should, however, an obstacle prevent the free rising of the table 6 the said spring connection permits the table to remain stationary against pressure of the spring consequently minimizing the liability of damage. The shaft 13 carrying the cam arm 12 is conveniently driven by a train of wheels 17—17a—17b from a motor driven shaft 18. The drive to this shaft 13 can be cut off by means of a dog clutch comprising pins 44 on the gear wheel 17 projecting from one side face which are adapted to engage perforations in a collar 45 rotating with and slidable on the shaft 13. The collar 45 is adapted to be moved into or out of engagement with the pins on the gear wheel 17 by means of a pivoted lever 46 having a hand grip 47. The table 6 is timed to rise to receive the material ejected by the piston and is allowed to fall after the said ejection, so that the material will be broken away from the discharge nozzle 4. It will of course be understood that if the material is liquid it will freely flow from the nozzle but if the material is of a viscous nature the cohesion of the material would normally leave a connection between the material in the pie casting or the like and that remaining in the nozzle. By lowering the table 6 a breaking action is effected and consequently a correct quantity is discharged, and moreover there is no liability of the material being pulled to the side of the pie casting when it is moved sideways. The nature of the material to be dealt with varies very considerably and in some cases further precaution may be neces-

sary in order to ensure that an exact predetermined quantity is delivered each time. In some classes of material the part remaining on the nozzle 4 may vary from one delivery to another 5 delivery, and in order to ensure that this will not be so a dividing device may be provided to cut off the material immediately under the delivery nozzle. For this purpose a wire 23 may be drawn across the nozzle following the delivery stroke 10 of the piston, and this wire is conveniently mounted on a slide 24 operated by the outlet slide valve 25 described in my said previous specification. The slide comprises a bar 24 mounted at the back of the frame of the delivery apparatus, and such bar adjustably carries the vertical arm 26a of an L-shaped bracket 26, the horizontal arm of which is U-shaped and carries the wire 23 across the mouth thereof. The vertical arm 26a slides in a vertical groove in a plate 27 20 carried by the slide bar 24 and is slotted to receive a fixing pin 28. The cutting wire 23 can therefore be arranged to suit varying lengths of nozzle and be adjusted in relation to the bottom of the nozzle. On the underside of the machine 25 casing, one end of a lever 29 is pivoted, the other end is slotted and connected to the slide bar 24. A slot is formed intermediate the end of this lever 30 and such slot is engaged by a pin 30 carried by the horizontally moving outlet slide valve 25 of the piston cylinder, the said pin 30 passing through a slot 31 in the delivery machine casing. The lever 29 imparts a longer stroke to the cutting off wire 23 than that of the slide valve 25 so that the stroke of the wire passes from a distance 35 on one side of the nozzle 4 to a distance on the other side of the nozzle, and is timed to pass under the nozzle slightly behind the closing movement of the inlet slide valve 32. By this means the exact amount of material held by the 40 nozzle is always the same.

Means are provided for automatically feeding a pie tin or the like on to the moving table 6 when it is at the bottom of its stroke. For this purpose a slide 33 is mounted in a slotted guide-way 34 on the stationary table 5, such slide having a forked end between the arms 33a of which a tin is placed. If the tin is round the arms 33a are shaped to form a tapering opening which will ensure that the tin will be automatically centered. 50 The slide 33 may, however, be adapted to receive any shape or kind of tin. If the tin is square the slide may have a rectangular slotted end to receive the tin. The slide is arranged to move laterally across the front of the machine and to 55 push the tin into position on the table 6, the slide then moving back before the table commences to rise. On the next stroke the tin already on the table is pushed off on to the stationary table 5 by the front of the tin then being placed on to the table 6. The slide 33 is operated by means of a lever 35 pivoted to one end on a pin 36 depending from the underside of the stationary table 5 and has a slot 37 at the other end which engages a pin 38 depending from the slide 33 and passing to the underside of the table 5. A pin or roller 39 on the lever 35 intermediate its ends bears against the end face of a rotating cam 40 and the lever is held against this cam face by means of a weight 41 mounted on the end of a cord 42 connected to the lever 35, the cord passing over the pulley 43. Should any obstacles get in the way of the slide 33 the only force which can be applied to the obstacles will be the pull of the said weight 41, and the 60 slide can be held stationary against this pull.

The cam 40 is mounted on the shaft 13 carrying the cam lever 12 operating the vertical moving table 6. The motor 19 also drives the reciprocating piston 1 through the medium of the gear wheels 20, 21 and 22. The stroke of the piston 1 is capable of being adjusted and for this purpose the piston connecting rod 48 has a longitudinal slot 49 in which a block 50, carried by the crank pin 51, slides and the amount of lost motion of the block 50 is adjusted by means of the slide 52 through which passes a screwed spindle 53. This screwed spindle is journaled in bearings 54 projecting from the side face of the connecting rod 48 and a knurled hand wheel 55 is fixed to the end of such spindle. When the slide 52 is adjusted to place the block 50 at the inner end of the slot 49 as shown in Figure 2 there is no lost motion and the piston makes a full length stroke. The distance between the slide block 50 and the inner end of the slot 49 is equivalent to the amount of lost motion, and whatever lost motion is allowed the piston 1 will always reach the same position in the cylinder 3 at the inner end of the stroke. A stirring tool 56 is mounted to rotate in the hopper 2 such stirrer being mounted on the end of a spindle 57 which carries a bevel gear wheel 58 which engages a bevel gear wheel 59 on the shaft 60. This shaft 60 is coupled to a shaft 61 by means of the reduced squared portion 60a engaging a square hole in the end of the shaft 61 so that by releasing the catch handle 62, the casing 63 carrying the bevel gears 58-59, shaft 60 and the stirring tool 56 can be easily detached to enable the hopper 2 to be filled. The shaft 61 is driven by the chain 64 from the shaft 65 which also drives the crank disc 66. The gear wheels 20, 21 and 22 are arranged in the casing 67 whilst the chain 64 is arranged in the casing 68 one end of which is fixed to the casing 67 whilst the other end is fixed to a bracket 69 attached to the side of the hopper 2. The inlet slide valve 32 and the outlet slide valve 25 are reciprocated by means of the cylindrical member 70 having a cam groove 71 around its periphery and engaged by the pins 72 on the slide valves. The member 70 is driven by gear wheels from the crank shaft 65.

I claim:

1. A machine for delivering jam, custard or other material in predetermined quantities into pie casings or containers, comprising a measuring chamber, a reciprocating piston for ejecting material from the measuring chamber through an outlet nozzle or opening therein, a slide for closing such outlet opening, a vertically reciprocating table for receiving a pie-casing or the like which is to be filled, automatic means for reciprocating the piston and for reciprocating the table to raise the pie casing or the like to receive the filling and for lowering the table to separate the filling material at the nozzle and for the removal and replacement of the pie casing or the like, a cutter which is actuated by the said slide valve to draw the cutter across the underside of the nozzle, comprising a cutting wire, a bracket on which the wire is mounted and is slidably mounted, and a lever, oscillated by connection to the slide valve or member operating the slide valve for oscillating the bracket carrying the cutter wire.

2. A machine for delivering jam, custard or other material in predetermined quantities into pie casings or containers, comprising a measuring chamber, a reciprocating piston for ejecting material from the measuring chamber through

- an outlet nozzle or opening therein, a vertically reciprocating table for receiving a pie casing or the like which is to be filled, automatic means for reciprocating the piston, automatic means for reciprocating the table comprising a continuous driven cam, a lever reciprocated by the said cam, a pivoted arm on the lever, a spring holding the arm against a stop on the lever and an abutment on the table against which the arm presses, with a pressure not greater than the said spring, for raising and lowering the table.
3. A machine for delivering jam, custard or other material in predetermined quantities into pie casings or containers, comprising a feed hopper, a horizontally directed measuring chamber, a piston reciprocating in the chamber, a crank shaft reciprocating the piston through the medium of a connecting rod, located at the rear of the feed hopper, a valve for closing the inlet to the measuring chamber, a valve for closing the outlet from the measuring chamber, means for automatically operating said valves, a table on the upper side of which is supported the said measuring chamber, a driving shaft mounted on the underside of the said table, means for driving the said crank shaft from said driving shaft, a vertically reciprocating table mounted in the stationary table, means for reciprocating the vertically reciprocating table from the said driving shaft to raise the pie casing or the like to receive the filling and for lowering the table to separate the filling material at the nozzle and for the removal and replacement of the pie casing or the like, means for feeding a casing to be filled on to the reciprocating table and for removing a filled casing therefrom, comprising a slide mounted in a slot arranged longitudinally in the stationary table which passes the casing over the stationary table to the reciprocating table, a lever pivoted to the underside of the table and moving in a plane parallel therewith coacting at one end with said slide, a cam mounted on said driving shaft for reciprocating the said lever and a cord carrying a weight at one end and connected to the lever for holding the lever in engagement with the cam.
